Limited, Doncaster, England

Application August 11, 1943, Serial No. 498,242
In Great Britain January 5, 1942

1 Claim. (Cl. 57—139)

This invention relates to fibre yarns for baling and binding and like purposes, and in particular in binding waste paper, cardboard, hay, straw, moss litter, wood wool, rags or other materials which are commonly baled.

Yarns for use in baling are often supplied in the form of cheeses, or balls formed by winding a single length of yarn upon itself with or without the use of a core, but in such case in order to obtain a large number of lengths of yarn, it is necessary to draw it off the cheese or ball and cut the lengths individually and in succession.

In order to minimise the labour in cutting a large number of equal lengths of yarn, the practice has been adopted to form a plurality of yarns into a strand which is wound upon itself to form a coil, cheese or the like so that a length of the strand may be unwound and the whole of the individual yarns forming the portion of the strand so unwound cut or severed from the remaining portion, after which the individual lengths of yarns in the severed length may be separated one from the other.

In forming such strands from a plurality of yarns, hitherto the usual practice in connection with the formation of strands for use in the manufacture of ropes has been followed, that is to say if the yarns are formed of fibres twisted in a right-hand or clockwise manner, a number have been formed into a strand of left-hand or anti-clockwise lay or vice versa.

In this way the individual yarns bind together in the strand owing to their opposite twists and do not tend in normal procedure to any considerable extent to untwist, a feature which of course is desirable in connection with strands to be employed in the production of standard ropes.

The result is that in separating the several yarns by pulling out the individual yarns from the severed length of strand, the lengths of yarn remaining stranded together become drawn-up or looped and the yarns are subjected to relatively considerable friction and the fibres are in consequence caused to fray out to a greater or lesser extent and the individual yarns are consequently weakened.

Further when a right-hand yarn is withdrawn from a left-hand strand or vice versa, the yarn in its passage along the strand takes up a spiral in an opposite direction to the lay of the yarn which tends to unlay the yarn, and this also tends to reduce the breaking load of the separated yarns.

Moreover, when a right-hand yarn is stranded 55 wise.

left-hand or vice versa, there is a further tendency in the process of stranding to take a certain amount of turn out of the yarn which in itself also has the effect of reducing the strength of the separated yarns relative to the initial breaking load of the yarn, before stranding.

The present invention is based upon the observation that after the individual yarns are formed of fibres with a right-hand twist and 10 such yarns are twisted together to form strands also of right-hand lay, the yarns tend to untwist and the difficulties above referred to in connection with the previous proposal do not arise, the position being the same when the individual yarns are spun left-hand and are formed into a strand which is of left-hand lay.

The yarns in the strands thus formed in accordance with the invention tend to unlay, separate and throw themselves out straight, all 20 strand formation is thus neutralised and the individual yarns can be picked out of the cut length. If any turn remained in the strand formation, the yarns, when withdrawn from the cut length, would follow a spiral which tends to put 25 turn into the yarn and the yarns would tend to tighten up in their lay instead of unlaying, thereby assisting in the retention of the original braking load of the individual yarns.

The tendency for the strand to become un- 30 twisted so that the individual yarns separate necessitates the adoption of certain precautions in handling the strand when cutting lengths thereof, and according to the invention to prevent the yarns forming the strand from untwisting materially or excessively beyond the position adjacent to that at which the strand is to be severed before the length of strand is cut, a sleeve, 35 collar, ring, thimble or the like operating to prevent the separation of the individual yarns is 40 passed over the strand to a point just beyond that where the cut is effected.

The invention thus consists in a package of 45 yarns the fibres of which are twisted in a given sense, direction or lay and formed into a strand twisted or laid in the like direction having slidably arranged on the free or outer end of the strand, a collar, sleeve, ring, thimble or the like adapted to restrain the yarns from unstranding or separating and to be passed along the strand 50 to the position adjacent to that at which it is to be severed.

By the expression "package" is included a coil, cheese or other body formed by winding or coiling a strand upon itself about a former or other-

The collar, sleeve, ring, thimble or the like may be formed of any suitable material, for instance, metal or plastic moulding compositions, and it may be a short length of cardboard or like felted pulp tubing. Conveniently, such a collar, sleeve, ring, thimble or the like may be applied to one end of the strand and thus be associated with the package into which the strand is formed during transport, storage and use.

The invention will be described further in detail and by way of example with reference to the accompanying drawing, in which—

Figure 1 illustrates a coil of the strand in accordance with the invention, and

Figure 2 is a view in elevation on a larger scale approximating actual size of a portion of the strand.

As shown in the drawing the strand 1 is formed of a plurality of yarns 2 and is formed by twisting the yarns in the same sense as the fibres 3 are twisted to form the yarns; in these figures the yarns and also the fibres are shown twisted in right-hand lay.

In order to prevent the strand untwisting, adjacent to one end there is located a sleeve 4 designed to be slid along the length of the strand to a position where it may be required to sever the strand, the individual yarns constituting the portion so severed from the coil untwisting or separating one from the other, that is to say turning in the direction reverse from that in which they have been twisted together in forming the strand, and to some extent twisting in the reverse direction, with the result that the individual yarns are more readily separated than would be possible if the several yarns had been twisted together in forming the strands in the

reverse direction from that in which the fibres had been twisted in forming the yarns, or in other words of the standard practice in forming strands from fibre yarns had been followed.

At this point it may be mentioned that it has been proposed in the manufacture of surgical bandages of wool or cotton to employ warp threads each of which consists of two or more strands or threads individually and collectively twisted in the same direction, that is to say right-hand twist on right-hand twist and left-hand twist on left-hand twist, the threads being given a number of twists adapted to double or even treble their normal torsion, such composite threads being employed on account of their retracting freely when left to themselves or when woven into a fabric, the bandage formed of such fabric thereby possessing great elasticity and power of contraction.

We claim:

A package of yarns adapted for use for binding or baling and like purposes, formed of fibres spun or twisted together in a given sense, direction or lay and combined into a strand having a lay of the like direction, having slidably arranged on the free or outer end of the strand a sleeve to restrain the yarns engaged in the sleeve from unstranding and separating and to enable the sleeve to be moved into a position in which a length of the yarn may be severed from the package and thus freed from the restraining action of the sleeve in order to facilitate unstranding or separating of the individual yarns.
